United States Patent Office.

ANTHONY J. ROBRECHT, OF NEWARK, NEW JERSEY.

Letters Patent No. 82,852, dated September 22, 1868.

IMPROVEMENT IN CARPET-BAGS.

The Schedule referred to in these Letters Patent and making part of the same.

TO ALL WHOM IT MAY CONCERN:

Be it known that I, ANTHONY J. ROBRECHT, of Newark, in the county of Essex, in the State of New Jersey, have made an Improvement in Travelling-Bags, Valises, and Trunks, especially as regards the partition in the same; and I do hereby declare that the following is a full and exact description thereof, reference being had to the accompanying drawings, and to the letters of reference marked thereon.

The nature of this improvement consists in so arranging said partitions (generally secured and made fast on the lower side, thus to allow a free and easy swing,) that they may be instantly and thoroughly detached therefrom, if the whole room is to be used as one chamber only; as also, in its turn, be replaced again without much labor.

I have accomplished this arrangement by means of eyes or hooks, fastened to the bag or trunk, and hooks or eyes fastened to the partition in a manner that each of such hooks and eyes serves as a hinge, and so constructed that a disconnection of both may be accomplished when expressly desired; otherwise a voluntary separation cannot take place.

On the same plan any number of partitions may be joined to each other, to serve as sample show-cards. Its great utility consists in the easy mode of joining and separating any one out of the rest.

Figures I and II are illustrations representing my improvement.

Fig. I. *a* is a travelling-bag, valise, or trunk, having two eyes fastened to the wire rod *d*, bottom, or any other convenient place of the frame. The partition *e* is lined at its bottom by a band, *f*, of thin sheet metal, embracing both sides about one-quarter of an inch, and is destined to stiffen and strengthen said partition. At the one end of the band a hook, *g*, is fastened, in order to engage the eye *c*, as a similar hook, *i*, at the other end, answers the eye *b*. This last-named hook, however, forms one end of a spring, *l*, which oscillates in an excavation, *m*, made in the partition, and passes also through a long hole of the band along the edge of said partition, so that the hook may either engage the eye or be withdrawn, whilst the other end, *n*, of said spring is secured to the band.

The operation is a simple one. I push the hook *i* into its eye, and hold the hook *g* opposite the hole of its eye, and withdraw again, whereby the partition is adjusted. It is obvious, therefore, that by a reciprocal manipulation a reciprocal result will be obtained. It is easily understood that any number of such hooks and eyes may be employed, according to the length of the partition, as also the number of the latter may be multiplied if more than two chambers should be wanted. For cheapness' sake, the hook *i* may be arranged without the spring *l*, by bending a piece of wire in the shape of a hook, as shown in Fig. II, *p*, so that the eye, by one certain direction given the partition, will have the chance to pass laterally into or out of the hook through the opening *q*.

I have now described my invention, and will state what I desire to secure by Letters Patent, viz:

I claim—

1. The combination of one or more partitions with a travelling-bag, valise, or trunk, produced by means of hooks and eyes, constructed to be employed in the manner and for the purpose specified.
2. The combination of the metallic band *f* with the partition *e*, and also the combination of said band with hooks or eyes, employed in the manner and for the purpose specified.

ANTHONY J. ROBRECHT.
